CLAIM

The ornamental design for a bottle, as shown and described.

DESCRIPTION

FIG. 1 shows a front perspective view of a bottle showing my new design;

FIG. 2 shows a front elevation view of the design shown in FIG. 1;

FIG. 3 shows a right elevation view of the design shown in FIG. 1;

FIG. 4 shows a left elevation view of the design shown in FIG. 1;

FIG. 5 shows a rear elevation view of the design shown in FIG. 1;

FIG. 6 shows a top plan view of the design shown in FIG. 1;

FIG. 7 shows a bottom plan view of the design shown in FIG. 1; and,

FIG. 8 shows a front perspective view of the design shown in FIG. 1, with components of the bottle in an alternate position.

The dash-dash broken lines in the drawings depict portions of the bottle that form no part of the claimed design. The dash-dot broken lines in the drawings define the bounds of the claimed design and form no part thereof.

1 Claim, 7 Drawing Sheets
